CLAIM

The ornamental design for a furniture, as shown and described.

DESCRIPTION

This application is related to commonly assigned, co-filed U.S. design patent application Ser. No. 29/792,659, filed on Apr. 14, 2022, by Jeffrey Taly, entitled “Planter”; commonly assigned, co-filed U.S. design patent application Ser. No. 29/792,660, filed on Apr. 14, 2022, by Jeffrey Taly, entitled “Table”; and commonly assigned, co-filed U.S. design patent application Ser. No. 29/792,661, filed on Apr. 14, 2022, by Jeffrey Taly, entitled “Seat”; which applications are incorporated herein by reference in their entireties.

FIG. 1 is a front right perspective view of a furniture according to the new design;

FIG. 2 is a rear left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof; and,

FIG. 9 is a front right perspective view of an alternative embodiment of the furniture having a symbolic break in the length and width of the design.

The broken lines in the drawings illustrate portions of the furniture and form no part of the claimed design.

The long dash-dot-long dash lines in the drawings represent a boundary of the claimed design.

The furniture is shown with a symbolic break in its length and width. The evenly dashed symbolic lines and the appearance of any portion of the article between the break lines forms no part of the claim.
